UNITED STATES PATENT OFFICE.

RICHARD WEBB BURNETT, OF MONTREAL, QUEBEC, CANADA.

CONVERTIBLE FLAT AND HOPPER BOTTOM DUMPING CAR.

1,081,205.

Specification of Letters Patent.

Patented Dec. 9, 1913.

Application filed July 18, 1912. Serial No. 710,264.

To all whom it may concern:

Be it known that I, RICHARD WEBB BURNETT, residing at the city of Montreal, Province of Quebec, Dominion of Canada, a citizen of the United States of America, have invented certain new and useful Improvements in Convertible Flat and Hopper Bottom Dumping Cars; and I do hereby declare that the following is a full, clear, and exact description thereof.

My invention relates particularly to cars for carrying loose commodities such as grain, coal, gravel, and the like, and it has for its object to simplify the construction of the car as a carrier for loose commodities, to simplify the construction of the hoppers of cars of this type and render more effective the joint between the adjustable floor parts of the car and the mouths of the hoppers.

My invention may be said to consist of the construction, combination and particular arrangement of parts hereinafter described and pointed out in the claims.

For full comprehension, however, of my invention, reference must be had to the accompanying drawings forming a part of this specification in which similar reference characters indicate the same parts, and wherein:

Figure 1 illustrates diagrammatically a transverse vertical sectional view of a convertible car containing my invention, with the parts arranged for service as a general freight-carrier; Fig. 2 is a similar view to Fig. 1 of one half only of the car, however, and drawn to a larger scale, the parts being arranged for service as a general freight carrier, and shown in dotted lines as arranged for a grain carrier; and Fig. 3 is a detail perspective view of the parts of the combined floor and grain door and the position of the fixed floor with which it is in hinged relation.

My improved car has a pair of hoppers disposed transversely and each consisting of a pair of vertical walls 2, 2, and a fixed inclined floor member, the latter being formed by the end portions of a plate member extending transversely to within comparatively close proximity to the sides of the car, the middle of this member resting on the center sill and being shaped to present oppositely facing angular door jambs 4, 4. It consists, preferably, of a pair of plates 5, 5 constituting the fixed floor members of the

hoppers, and the door-jamb portion is preferably formed of a separate metal plate 6 bent to the form required, the edges of all three plates being riveted together and to the center sill as at 7. The end edges of these inclined floor members are attached to the bottom edges of the vertical side walls 2, thus forming chutes, the discharge mouths of which are disposed in angular positions slightly removed from the perpendicular plane of the sides of the car. Relatively small doors 12 close the mouths of these chutes, and, like these mouths are, when closed, in position inclined only slightly from the vertical. A serious defect in cars of this type has been the misfit of the floor members and the unavailability of the grain doors when required. I overcome these defects by providing a displaceable telescopic floor member adapted to displace any grain and the like left on the center sill or other members of the under frame on which these displaceable floor members rest. The specific device for the purpose comprises a member 60 made up of tongue-and-groove boards arranged longitudinally with relation to the car, and fastened together by metal bands 69 on opposite sides of this door member and braced by a series of angle-irons 61, half the length of each of which is riveted in place and the remainder sprung out slightly as at 62 to accommodate the extensible member to be presently further alluded to. This floor member is hinged to the fixed floor members 63 of the car by means of trunnions 65 fastened to the door by plates 66 to which they are welded, such plates being riveted or bolted in place, and a plate 67 of half D-form with its angle disposed so as to bear on the top of the side sill and against a threshold strip 68 when the member 60 is raised and thus act as a grain seal, and, at the same time, serve as a stop limiting the outward movement thereof and taking up some of the stress which would otherwise be carried entirely by the door frame in the side of the car. The trunnions are journaled in sockets beneath the contiguous edges of the fixed floor members in which are mounted offset plates 70 confining the trunnions between them, the side of the car-body and the top of the side sill. The fixed floor members are securely fastened in place by being bolted or riveted to the underframing. The free edges of these members 60 are beveled to coincide

and make contact with the diagonal jambs 4, 4, on the center sill.

What I claim is as follows:

1. In a car for loose commodities, the combination with a side sill and center-sill, of a discharge hopper comprising vertical walls hung from the car body, a diagonal hopper floor member carried by the walls and extending substantially the full length and width of the hopper, such diagonal floor member consisting of a pair of parts constituting the floors of the respective hoppers and a central part uniting the said floor parts and having an angular rib presenting opposite diagonal door-jambs and a pair of combined floor members and grain-doors hinged contiguous to the sides of the car and having beveled free edges for engagement with the door-jambs.
2. In a convertible car the combination with the under framing and body, of a pair of combined floor and grain-door members hinged contiguous to the sides of the car and collectively extending from side to side of the car, discharging hoppers beneath the floor having diagonal fixed floors consisting of a member extending transversely of the car and including an angular middle part

extending longitudinally of the car and mounted on the under framing, the said part 30 presenting oppositely inclined door-jambs for engagement by the combined floor and grain-door members.

3. In a convertible car the combination with the under-framing and body, of a pair 35 of extensible combined floor and grain-door members hinged contiguous to the sides of the car and collectively extending from side to side of the car, discharging hoppers beneath the floor having diagonal fixed floors 40 consisting of a member extending transversely of the car and including an angular middle part extending longitudinally of the car and mounted on the under framing, the said part presenting oppositely inclined 45 door-jambs for engagement by the combined floor and grain-door members.

In testimony whereof I have signed my name to this specification in the presence of two witnesses.

Montreal, July 3rd 1912.

RICHARD WEBB BURNETT.
